(57) **CLAIM**

I claim the ornamental design for outdoor water sports sunglasses, as shown and described.

DESCRIPTION

FIG. 1 is a perspective view of outdoor water sports sunglasses showing my new design;

FIG. 2 is a Front view thereof;

FIG. 3 is a Back view thereof;

FIG. 4 is a Right-side view thereof;

FIG. 5 is a Left-side view thereof;

FIG. 6 is a bottom plan view thereof; and,

FIG. 7 is a top plan view thereof.

The broken lines in the drawings depict portions of the outdoor water sports sunglasses that form no part of the claimed design.
